UNITED STATES PATENT OFFICE.

CHARLES D. KELLY AND PATRICK MAHONEY, OF OAKVIEW, PENNSYLVANIA.

CONCRETE ARCH.

1,074,268.

Specification of Letters Patent. Patented Sept. 30, 1913.

Application filed March 29, 1912. Serial No. 687,263.

To all whom it may concern:

Be it known that we, CHARLES D. KELLY and PATRICK MAHONEY, citizens of the United States, residing at Oakview, county 5 of Delaware, and State of Pennsylvania, have invented certain new and useful Improvements in Concrete Arches, of which the following is a specification.

Our invention relates to improvements in 10 concrete arches, the object of the invention being to provide an improved concrete arch which may be constructed without bracing from below, and which is efficiently reinforced by wires connecting vertical piers.

15 A further object is to provide an improved construction of the character described which may be built out from pier to pier from above, utilizing the reinforcing of the arch as a support for the boards constituting the bottom or arch mold.

20 With these and other objects in view, the invention consists in certain novel features of construction and combinations and arrangements of parts, as will be more fully 25 hereinafter described and pointed out in the claims.

In the accompanying drawings: Figure 1, 30 is a view in longitudinal section illustrating the arch showing the arrangement of supporting wires and boards. Fig. 2, is a view in transverse section on the line 2—2 of Fig. 1. Fig. 3, is a plan view on a reduced scale, and Fig. 4, is a view in section on the line 4—4 of Fig. 1.

35 In carrying out our invention, the piers 1, 1, are formed and on their upper portions are shaped as shown at 2. In other words, these piers are provided with shoulders 3 which extend inwardly the desired distance 40 to receive and support the end of the arch connecting the piers. As the piers are being built, when they reach a certain height, U-shaped wires 4 are laid in the concrete and are provided on the outer faces of the 45 piers with eyes 5. At a higher elevation, similar U-shaped wires 6 are laid in the piers, and they are provided on their inner ends with eyes 7. By reason of these U-shaped wires, they cannot pull out of the 50 piers, and form perfect anchors. After the piers are completed, wires 8 are connected at their ends to the eyes 5, and are drawn taut over the upper ends of the piers. Other 55 wires 9 are connected at their ends to the eyes 7, and these wires are relatively slack.

After the wires 8 are secured in place,

boards or timbers (not shown) may be supported on these wires to allow workmen to move out over the same and connect the wires 8 with the wires 9 by means of hooks 60 10. These hooks vary in length, the shortest hook being centrally between the piers, and the longest hook adjacent the piers, so that while the upper ends of the hooks are all in alinement, the lower ends are in the 65 arc of a circle and support the wires 9 in this position.

The outer set of hooks 10 serve to hold 70 timbers 11 against the sides of the arch, while transversely positioned boards 12 are supported on the wires 9 between the hooks 10. The timbers 11 and the boards 9 form a mold for the arch, but the arch is built out gradually from the piers toward the center. In other words, the concrete is placed first 75 adjacent the piers, working, of course, from above. This first concrete will rest upon the shoulders 3 of the piers, and working from both piers toward the center, the concrete gradually reaches the center of the arch. 80 This concrete is built out in instalments, allowing certain portions to set before other portions are added. When the concrete reaches the center of the arch, and becomes set, the timbers 11 and the parts 12 are removed. Portions of the wires and hooks 85 will, of course, be embedded in the concrete structure, and any projecting ends may be cut off and the surface suitably troweled so as to leave it smooth and free from obstructions. 90

By reason of this method, we are enabled 95 to build the arch from above, without providing any supports underneath the arch which are difficult to place in position, difficult to remove, and add greatly to the cost of building.

Various slight changes might be made in 100 the general form and arrangement of parts described without departing from our invention, and hence we do not limit ourselves to the precise details set forth, but consider ourselves at liberty to make such changes and alterations as fairly fall within the spirit and scope of the appended claims. 105

Having thus described our invention, what we claim as new and desire to secure by Letters Patent is:

110 1. A reinforced concrete structure of the character described, comprising piers having shoulders on their opposed faces at their upper ends, wires anchored in the piers and

forming eyes at the inner and outer faces of the piers, wires secured to the eyes on the outer faces of the piers and extended over the upper ends of the piers, other wires connecting the eyes at the inner faces of the piers, and longer than the distance between the piers, and hangers connecting the wires extended across the top of the piers with the last-mentioned wires, said hangers of different lengths, whereby the last-mentioned wires are arched, and concrete material extended from shoulder to shoulder of the piers, substantially as described.

2. A reinforced concrete structure of the character described, comprising piers having shoulders on their opposed faces at their upper ends, wires anchored in the piers and forming eyes at the inner and outer faces of the piers, wires secured to the eyes on the outer faces of the piers and extended over the upper ends of the piers, other wires connecting the eyes at the inner faces of the

piers and longer than the distance between the piers, and hangers connecting the wires extended across the top of the piers with the last-mentioned wires, said hangers of different lengths, whereby the last-mentioned wires are arched, and concrete material extended from shoulder to shoulder of the piers, said concrete extended over the upper ends of the piers embedding that portion of the wire on top of the piers and embedding the hangers throughout the greater portion of their length, substantially as described.

In testimony whereof we have signed our names to this specification in the presence of the subscribing witnesses.

CHARLES D. KELLY.
PATRICK X MAHONEY.
